(57) **CLAIM**

The ornamental design for a lunch bag, as shown and described.

DESCRIPTION

FIG. 1 is a top perspective view of a lunch bag showing my new design.

FIG. 2 is a bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines on the handle and strap attachment in FIGS. 1-7 are included to show claimed stitches on the lunch bag. Other broken lines illustrate portions of the lunch bag that form no part of the claimed design.
